UNITED STATES PATENT OFFICE.

ROBERT H. STOKER, OF HOUSTON, OHIO.

PUMP.

1,399,669.

Specification of Letters Patent.

Patented Dec. 6, 1921.

Application filed March 22, 1921. Serial No. 454,553.

To all whom it may concern:

Be it known that I, ROBERT H. STOKER, a citizen of the United States, residing at Houston, in the county of Shelby and State 5 of Ohio, have invented new and useful Improvements in Pumps, of which the following is a specification.

This invention relates to means for converting a rotary movement into a reciprocatory movement and the device is designed 10 for use on pumps, stamping mills, well drilling machines and the like.

The principal object of the invention is to provide an arrangement of eccentrics with 15 means for causing one eccentric to move the reciprocating part in one direction and another eccentric to move said member in the opposite direction.

Another object of the invention is to provide the eccentrics with movable straps or 20 bands and with means for connecting and disconnecting the straps or bands with the eccentrics in such a manner that when one of the bands is in engagement with its eccentric to give the reciprocating member one stroke the other band is free of its eccentric so that said band and the connecting 25 parts can rotate on the eccentric to a position where they will be ready to give the reciprocating member its return stroke after 30 the completion of the first stroke.

A further object of the invention is to provide automatically operating dogs for engaging and disengaging the bands or 35 straps with their eccentrics.

This invention also consists in certain other features of construction and in the combination and arrangement of the several parts, to be hereinafter fully described, 40 illustrated in the accompanying drawings and specifically pointed out in the appended claims.

In describing my invention in detail, reference will be had to the accompanying 45 drawings wherein like characters denote like or corresponding parts throughout the several views, and in which:—

Figure 1 is an elevation of the invention showing the same in use on a pump.

50 Fig. 2 is a view taken at right angles to Fig. 1.

Fig. 3 is an enlarged view of one set of eccentrics and their associated parts.

Fig. 4 is a section on line 4—4 of Fig. 3.

55 Fig. 5 is a fragmentary sectional view

showing the operating means for the dogs of one pair of eccentrics.

Fig. 6 is a fragmentary sectional view showing the dog receiving recesses in one of the eccentrics and its strap with the dog 60 in the recess in the strap.

Fig. 7 is a diagrammatic view showing the parts in a position at the completion of the lifting stroke and the beginning of the down stroke.

Fig. 8 is a similar view showing the position of the parts at the beginning of the lifting stroke.

In these views 1 indicates a rotatable shaft to which the two sets of eccentrics A 70 and B are secured. The sets comprise the small lifting eccentrics 2 and 2' and the large lowering eccentrics 3 and 3'. The eccentrics of each set are connected together so as to move as one element and each eccentric is grooved to receive the straps or bands 4 and 4'. Each eccentric is provided with a recess 5 and the recess of each large eccentric has its bottom wall provided with teeth 6. Each strap is provided with 75 a recess 7. A dog 8 is pivotally mounted in the recess 7 in each strap 4 of the large eccentrics and a dog 8' is pivotally mounted in the recess of each small eccentric. Each dog is controlled by a spring 9 which 80 tends to force the dog out of the recess and into the recess 5 of the eccentric. The dogs 8 have teeth on their lower edges, but the dogs 8' do not.

As a matter of convenience the large eccentrics are referred to as the downstroke eccentrics or lowering eccentrics. As used with a pump and as shown in the drawings, however, these large eccentrics simply act to prevent the parts from dropping downwardly under the action of gravity. These eccentrics support the parts and permit them 95 to lower gradually.

I provide trip means for lifting the dogs out of the recesses in the eccentrics to free 100 the straps from the eccentrics and such means consists of a shaft 10 carried by each set of eccentrics and passing through the same adjacent the shaft 1. The opening for said trip shaft 10 is in communication with the grooves for the straps of both the large and small eccentrics and the portions of the shaft adjacent said grooves are toothed, as at 11. The opening for said shaft 10 is also 105 in communication with the recesses 5 in the 110

eccentrics so that the toothed portions 11 of shaft 10 will engage the teeth 12 on the ends of dogs 8 when said dogs are in the recesses 5 so that when said shaft is rotated said 5 dogs will be lifted out of the recesses 5 into the recesses 7 in the straps. The outer end of the shaft 10 is provided with a toothed wheel 13 which is adapted to engage with a pair of toothed segments 14 secured to the 10 supporting frame of the device, these segments 14 being so arranged that they will cause shaft 10 to rotate to move the dog 8 of the large eccentric into the recess in the strap at the beginning of the up stroke of 15 the device and to move dog 8' out of the recess 5 of the small eccentric at the end of the lift stroke.

20 A forked pitman rod 15 connects each of the straps 4 of the large eccentrics with the pump rod and a flexible member 16 has its lower end connected with the cross head of the pump and its upper end connected with the strap 4' of each of the small eccentrics. These flexible members pass over the idlers 25 17 which are suitably supported on the supporting frame.

Fig. 1 shows the set of eccentrics A in a 30 position with the small eccentric engaged with its strap and the large eccentric disengaged from its strap. Eccentric 2, at the start of its lifting stroke is off center, while eccentric 2' is carrying the load at full speed and is nearing the completion of the stroke. The strap of the large eccentric of set A 35 will move anti-clockwise upon its eccentric as soon as the small eccentric of this set starts to raise the pump piston. The set B will have reached the end of the stroke when they reach the line E—E. At this 40 point the strap of the small eccentric of set B will be disengaged from its eccentric by the toothed wheel 13 engaging the top segment 14 and the strap of the large eccentric of set B will be engaged with its eccentric 45 by its dog moving into the recess 5 so as to carry the pitman from the dotted line E—E to the bottom of the stroke. As this large eccentric forces the parts downwardly the flexible member will be unwound from 50 the small eccentric causing the eccentric strap to rotate in a counter clockwise direction. As shown the dogs are placed near the center of rotation where the speed is the least. When the small eccentric of set B has 55 completed its stroke the other small eccentric will have taken the load and attain full speed on the dotted line E—E.

The rotary motion of the eccentric head 60 produces a straight line reciprocating movement of the pump pistons by the simple winding of the flexible members on the periphery of the eccentric bands as they rotate, the bands being engaged to the eccentrics when the upward stroke is being made; and 65 as the eccentrics are oppositely keyed to the

shaft, they raise their pistons on the upward stroke alternately. Each eccentric carries the load through a little more than a full half revolution. While one eccentric is carrying the load past the center near the 70 end of its stroke the other eccentric is starting at the beginning of the upward stroke, off of center at no speed, see Fig. 1. It gradually increases in speed and assumes the 75 load and has attained full speed at the instant the other stroke is completed. Consequently dead centers are positively eliminated, and the load being carried at all times on the same radius, the water column must travel at the same speed at all times, making 80 pulsation in the discharge or flow impossible, as well as any jerk, jar, vibration, water hammer, back lash or any uneven strain or irregularity whatever. As the eccentric head rotates and the lifting eccentric 85 raises its cross head with its rods and water load, the pitman rod, being connected to the cross head and to the eccentric band of the downstroke eccentric, must raise with it. In raising, it moves this eccentric band back in 90 the opposite direction to which the head is rotating, and when the upward stroke is completed the point at which the pitman rod is connected to the eccentric band will be in the same position on the eccentric as when 95 starting at the beginning of the upward stroke. At the instant of the completion of the upward stroke, the band on the lifting eccentric is disengaged from the eccentric and the band on the down stroke eccentric 100 is simultaneously engaged to its eccentric, and travels with the eccentric carrying all the weight of pitman, cross head and pump rods back on the down stroke to the beginning of the upward stroke. The flexible 105 member connecting the cross head and the lifting eccentric is unwound as the cross head descends, drawing back in opposite direction from the rotation of the head, the band of the lifting eccentric, to the same 110 position as at the beginning of the upward stroke. At this point in the revolution, the lifting eccentric band is engaged to the eccentric and the down stroke eccentric band is simultaneously disengaged from its 115 eccentric. When the bands are moving on the eccentrics there is no load whatever on them, either on lifting or down stroke eccentrics. Consequently there is practically no friction, and when carrying the load, being engaged 120 to their eccentrics, there can be no friction.

While the drawings show the invention in use on a pump it will of course be understood that it may be used on other devices such as well drilling machines, stamping mills and the like.

It is thought from the foregoing description that the advantages and novel features of my invention will be readily apparent.

I desire it to be understood that I may 130

make changes in the construction and in the combination and arrangement of the several parts, provided that such changes fall within the scope of the appended claims.

5. What I claim is:—

1. A device of the class described comprising a rotatable shaft, a set of eccentrics thereon including a small lifting eccentric and a large downstroke eccentric, straps 10 slidably engaging the eccentrics, a reciprocating member, means for connecting the said member with the straps and means for engaging one strap with its eccentric and disengaging the other strap from its eccentric.
15. 2. A device of the class described comprising a rotatable shaft, a pair of eccentrics thereon connected together and including a lifting eccentric and a downstroke eccentric, straps for the eccentrics slidably mounted thereon, a reciprocating member, a flexible member connecting the reciprocating member with the strap of the lifting eccentric, a pitman connecting the recipro-

cating member with the strap of the upstroke eccentric and means for engaging the strap of the lifting eccentric therewith and disengaging the strap of the downstroke eccentric therefrom for the upstroke and disengaging the strap of the lifting eccentric 30 and engaging the strap of the downstroke eccentric therewith for the downstroke.

3. A device of the class described comprising a rotatable shaft, a pair of reciprocating members, two sets of eccentrics on the 35 rotatable shaft, each set consisting of a small lifting eccentric and a large downstroke eccentric, straps for the eccentrics rotatably mounted thereon, a flexible member connecting the strap of each lifting eccentric with a 40 reciprocating member, a pitman connecting the strap of each down stroke eccentric with a reciprocating member, dogs for automatically engaging the straps with the eccentrics and trip means for disengaging the dogs to 45 free the straps from the eccentrics.

In testimony whereof I affix my signature.

R. H. STOKER.
